UNITED STATES PATENT OFFICE

2,009,000

CIGARETTE MOLD

George Zint, Wapakoneta, Ohio

Application September 18, 1934, Serial No. 744,569

7 Claims. (Cl. 131—5)

The invention relates to a new and improved device readily carried in the user's pocket and adapted for making cigarettes, the principal object of the invention being to provide a simple, inexpensive, rapid and easily operable article which will tightly roll the cigarette paper around the tobacco and will allow easy sealing of the paper without danger of loosening.

Another object is to provide a novel method for connecting the cigarette with a cigarette holder while it is being formed, said holder having a portion extending into one end of the cigarette and therefore occupying part of the space usually filled with tobacco. Thus, while less tobacco is used in each cigarette and more cigarettes may therefore be rolled from a package of tobacco, each of the cigarettes will burn as long as it usually takes an ordinary cigarette to burn from the tip to the saliva-soaked butt.

With the foregoing in view, the invention resides in the novel subject matter hereinafter described and claimed, description being accomplished by reference to the accompanying drawings.

Fig. 1 is a perspective view showing the device open in readiness for use and illustrating the cigarette paper and the cigarette holder in dotted lines.

Fig. 2 is a perspective view showing the parts in the relative positions which they occupy immediately after a cigarette has been rolled by the device.

Fig. 3 is a rear perspective view.

Fig. 4 is a sectional perspective view showing a partly formed cigarette in the device but showing the clamp member 19 raised from its paper-holding position.

Fig. 5 is a view similar to Fig. 4 but showing the cigarette paper rolled around the tobacco and held in rolled condition.

Fig. 6 is a view similar to Figs. 4 and 5 but illustrating the device opened in readiness for sealing the cigarette.

Fig. 7 is a detail perspective view, in section of a different plane from Fig. 5.

A preferred construction has been illustrated and will be rather specifically described, with the understanding however, that within the scope of the invention as claimed, variations may be made. Then too, while sheet metal is preferably used in constructing the article, other appropriate material or materials could, of course, be employed.

The article includes a molding trough 10 having parallel end plates 11 and 11' which project rearwardly therefrom; said end plates 11 and 11'

being preferably identical except that the plate 11' is formed with an opening 12 through which to insert the cigarette holder 13. The bottom 14 and the front wall 15 of the trough 10 are preferably integral with each other but the back wall 16 is by preference hinged at its lower edge to said bottom 14, as shown at 17.

A clamp extends between the end plates 11 and 11' along the upper edge of the back wall 16, said clamp preferably comprising a strip 18 whose ends are secured to said end plates 11 and 11', and a pivoted clamping member 19 which is pivotally supported upon a wire or the like 20 whose ends are secured to the rear ends of said plates 11 and 11'. The member 19 is formed with teeth 21 which pass through the cigarette paper into openings 22 in the strip 18 to tightly hold one edge of said paper as hereinafter described.

In the present showing, two fingers 23 are bent upwardly from the strip 18 to limit the insertion of the cigarette paper into the clamp 18—19, and two other fingers 24 are bent downwardly from said strip to limit the outward swinging of the hinged back wall 16 of the trough 10. This wall 16 is provided at its rear side with a finger-piece 25 which is instrumental in pushing it forwardly when sealing the cigarette, but a spring 26 which is secured to the strip 18 normally acts against said finger-piece to swing the wall 16 rearwardly to the limit allowed by the fingers 24.

A transversely curved gate 27, co-extensive in length with the trough 10, is hinged to the upper edge of the front wall 15 of said trough, as denoted at 28, said gate having a combined stiffening flange and finger-piece 29 by means of which it may be swung rearwardly and downwardly to curve the cigarette paper over the tobacco and tuck in the free edge of the paper between said tobacco and the portion of the paper which lies against the rear wall 16 of the trough. Provision is made for holding this tucked-in edge of the paper while the clamping member 19 and the gate 27 are open, so that the cigarette paper may be sealed without danger of it becoming loosened.

In the present disclosure, the holding means for the tucked-in edge of the cigarette paper, is in the form of a spur 30 carried by a spring arm 31 which is disposed in the angle between the strip 18 and the back wall 16 and is secured to the end wall 11'. The spur 30 is forwardly projectable through an opening 32 in the back wall 16, to penetrate the overlapped portions of the cigarette paper and hold them against relative movement while the paper is being moistened.

and sealed. While one sharp pointed spur is shown, more than one could be used if desired and each spur could have a blunt instead of a sharp end. A suitable pivoted latch 33 is provided for holding the spur-carrying spring arm 31 in spur-projected position until the cigarette paper has been sealed. Another latch 34 is pivoted upon one end of the rod 20 between the clamping member 19 and the end wall 11 for engagement with the flange 29 of the gate 27 to hold the latter closed when the device is being carried in the user's pocket. The member 19 is held in its closed position by frictional engagement with the latch 33 at one end and the end plate 11' at the other end.

In using the device, the latch 34 is first released and the gate 27 is fully opened. The clamping member 19 is then opened sufficiently to permit one edge of the cigarette paper (preferably a gummed edge) to be inserted under said member 19 to the limit allowed by the stop fingers 23. The clamping member 19 is then closed to clamp the cigarette paper and the latter is pushed downwardly into the trough 10. The cigarette holder 13 is now inserted through the opening 12 into the trough 10 for a distance of substantially three-quarters of an inch, said holder of course lying upon the cigarette paper which has taken the shape of the trough. Tobacco is now poured evenly into the cigarette paper between the holder 13 and the end plate 11'. Then, the gate 27 is swung rearwardly and downwardly, so that the free edge P' of the cigarette paper P is tucked in between the tobacco and the portion P'' of the paper P which lies against the back wall 16 of the trough 10, said edge P' being also tucked snugly between the portion P'' of the cigarette paper and the holder 13. In other words, the cigarette paper is tightly rolled around both the inner end of the holder 13 and the tobacco. The spur 30 is now projected inwardly through the opening 32 by pressing upon the spring 31, so that said spur passes through the overlapped portions P' and P'' of the cigarette paper and holds them against any relative slippage, the spring arm 31 being held in its spur-projected position, by means of the latch 33. With the cigarette paper thus held, the clamping member 19 and the gate 27 may be fully opened without danger of causing the paper to slip and loosen the cigarette. With the clamping member 19 opened, the previously clamped edge of the cigarette paper may be readily dampened with the tongue or with one finger, allowing the cigarette to be sealed in the usual way. To facilitate moistening the edge of the cigarette paper, the entire cigarette may be compressed somewhat from front to rear by pushing upon the finger-piece 25 and swinging the trough wall 16 inwardly. This movement of the wall moves the previously clamped edge of the cigarette paper to a more accessible position for dampening. After the paper has been sealed, the latch 33 is released and the cigarette, with the holder 13 attached to it, is withdrawn in readiness for use. While the holder is preferable, it will be obvious that cigarettes can be formed by the invention, without using said holder. It will also be clear that while excellent results are attainable from the details disclosed, numerous variations may be made within the scope of the invention as claimed.

I claim:

1. A cigarette mold comprising an elongated transversely curved trough in which to lay a cigarette paper in readiness to receive tobacco, a

clamp extending along the upper edge of the rear wall of said trough to hold one edge of the cigarette paper, a transversely curved gate coextensive in length with said trough and hinged to the upper edge of the front wall of said trough, said trough being of such width that the free edge portion of the cigarette paper will project beyond it and overlie said gate, said gate being adapted for rearward and downward swinging to curve the cigarette paper over the tobacco and tuck said free edge portion of the paper in between the tobacco and the portion of the paper against said rear wall of said trough, and paper-engaging means carried by said trough for holding the tucked-in edge portion of the paper, whereby said gate and said clamp may be opened and the paper sealed without danger of loosening.

2. A cigarette mold comprising an elongated transversely curved trough in which to lay a cigarette paper in readiness to receive tobacco, a clamp extending along the upper edge of the rear wall of said trough to hold one edge of the cigarette paper, a transversely curved gate coextensive in length with said trough and hinged to the upper edge of the front wall of said trough, said trough being of such width that the free edge portion of the cigarette paper will project beyond it and overlie said gate, said gate being adapted for rearward and downward swinging to curve the cigarette paper over the tobacco and tuck said free edge portion of the paper in between the tobacco and the portion of the paper against said rear wall of said trough, and manually projected paper-penetrating means projectable through said rear wall of said trough for holding the tucked-in edge portion of the paper, whereby said gate and said clamp may be opened and the paper sealed without danger of loosening.

3. A cigarette mold comprising an elongated transversely curved trough in which to lay a cigarette paper in readiness to receive tobacco, a clamp extending along the upper edge of the rear wall of said trough to hold one edge of the cigarette paper, a transversely curved gate coextensive in length with said trough and hinged to the upper edge of the front wall of said trough, said trough being of such width that the free edge portion of the cigarette paper will project beyond it and overlie said gate, said gate being adapted for rearward and downward swinging to curve the cigarette paper over the tobacco and tuck said free edge portion of the paper in between the tobacco and the portion of the paper against said rear wall of said trough, a manually operable spring arm mounted behind said rear wall of said trough and having a spur projectable forwardly through said rear wall to hold the tucked-in edge portion of the paper, and means for holding said spring arm when sprung to spur-projected position, whereby said gate and said clamp may be opened and the paper sealed without danger of loosening.

4. A structure as specified in claim 1; said rear wall of said trough being hinged at its lower edge and being adapted for inward swinging to facilitate sealing of the cigarette paper.

5. A cigarette mold comprising two parallel end plates, a transversely curved trough extending between and secured to said end plates, said trough having a hinged rear wall, a strip extending longitudinally of the upper edge of said rear wall and secured at its ends to said end plates, a hinged clamping member extending between

5 said end plates and cooperable with said strip in forming a clamp for one edge of a cigarette paper laid in said trough, a transversely curved gate extending along the upper edge of the front wall of said trough, said trough being of such a width that the free edge portion of the cigarette paper will project forwardly therefrom and overlie said gate, said gate being hinged to swing rearwardly and downwardly to curve the cigarette paper over 10 the tobacco and tuck said free edge portion of the paper in between the tobacco and the portion of the paper against said rear wall, and a manually projectable paper-penetrating spur mounted behind said rear wall under the afore- 15 said strip, said spur being forwardly projectable through said rear wall to hold said tucked-in edge portion of the paper, whereby said gate and said clamping member may be opened and said rear

wall pushed inwardly, allowing sealing of the cigarette paper without danger of loosening.

6. In a cigarette mold, co-operable relatively fixed and movable members for curving a cigarette paper around the tobacco and overlapping the edge portions of the paper, and paper-engaging means for holding said overlapped paper portions against relative slipping while opening said movable member to seal the cigarette paper. 5

7. In a cigarette mold, co-operable relatively fixed and movable members for curving a cigarette paper around the tobacco and overlapping the edge portions of the paper, and a manually projectable paper-penetrating spur for holding said overlapped paper portions against relative 10 slipping while opening said movable member to seal the cigarette paper. 15
